ABSTRACT: Urethanes consisting of a 2-hydroxy-1,1'-diphenyl ketone having an R-NH-CO-O- group in 4-position and wherein R e.g. represents an alkyl or an aryl radical. These urethanes are useful as stabilizers for organic material and above all as agents for combatting harmful micro-organisms.

HYDROXYPHENYL URETHANES

The subject of the present invention are new urethanes of general formula

(1)

wherein X denotes a hydrogen atom, a halogen atom, a hydroxyl group, an alkyl group or an alkoxy group, Y denotes a hydrogen atom, a halogen atom, a hydroxyl group, an alkyl group, an alkoxy group, or a $R_1-NH-CO-O-$ residue, Z denotes a hydrogen atom, a halogen atom, an alkyl group or a phenyl group, and R denotes an alkyl, halogenalkyl, alkenyl or cycloalkyl group or an optionally substituted phenyl group. In the case where R represents a substituted phenyl group, preferred substituents are a halogen atom, a halogenalkyl group, an alkyl group or an alkoxy group.

Preferred urethanes correspond to the formula

(2)

wherein X_1 denotes a hydrogen atom, a halogen atom, a hydroxyl group or an alkyl group having one to four carbon atoms, Y_1 denotes a hydrogen atom, a halogen atom, a hydroxyl group or an $R_1-NH-CO-O-$ residue, Z_1 denotes a hydrogen atom, a halogen atom, a phenyl group or an alkyl group having one to four carbon atoms and R_1 denotes an alkyl group having one to 12 carbon atoms or a residue of formula

wherein U and V each denote a hydrogen atom, a halogen atom, a trifluoromethyl group, an alkyl group having one to four carbon atoms or an alkoxy group.

Amongst the urethanes of formula (2), compounds of formulas (3) to (5) below demand very especial interest:

(3)

(4)

(5)

In formulas (3) to (5) the symbols denote the following: X_2 , Y_2 and Z_2 each denote a hydrogen atom, a halogen atom or an alkyl group having one to four carbon atoms, Y_3 denotes a hydrogen atom, a halogen atom or an alkyl group having one to four carbon atoms, Z_3 denotes a hydrogen atom, a halogen atom, an alkyl group having one to four carbon atoms or an $R_1-NH-CO-O-$ residue. R_1 has the significance mentioned.

A suitable urethane of formula (5) for example corresponds

to the formula

10 Amongst the urethanes of formulas (3) to (5), the urethanes of formula

wherein U and V have the significance mentioned, are in turn very especially preferred. Urethanes which are derived from formula (7) for example correspond to the formulas

The urethanes of formula (1) may be obtained according to the usual processes for obtaining urethanes.

The urethanes of formula (1) are manufactured by reacting 55 1 mol of a compound of formula

65 with 1 or 2 mols of a compound of formula

(13) $R-B$
wherein A and B denote residues which are able to form the bridge

by condensation or addition, and R, X, Y and Z have the significance mentioned.

An embodiment of this process consists of reacting a phenol of formula

(14)

with an isocyanate of formula

wherein R, X, Y and Z have the significance mentioned.

Depending on the starting products and molar ratios, the reaction can for example take place in accordance with the following scheme:

Preferably isocyanates are reacted with appropriate phenols. The phenols used as starting substances are either known or can be manufactured according to methods which are in themselves known. The following are for example used as isocyanates: 4-chloro-3-trifluoromethylphenyl isocyanate, 3,5-di-(trifluoromethyl)-phenyl isocyanate, 3,4-di-(chloro)-phenyl isocyanate or phenyl isocyanate.

The reaction can be effected in a solvent, for example in benzene, toluene, xylene or dioxane.

In order to accelerate and complete the reaction, it is advantageous to work in the presence of a tertiary base such as triethylamine, 1,4-diazabicyclo-(2,2,2)-octane ("triethylene diamine") and the like.

In another embodiment of the process a reactive derivative of carbonic acid, for example phosgene, may be reacted with an amine of formula (13) [$B=\text{NH}_2$] and a phenol of formula (14) in optional sequence, and in terms of formulas this can be indicated as follows:

Urethane of formula (1) + HCl

The urethanes of formula (1) simultaneously show two effects, namely as stabilizers and, above all as agents for combatting harmful micro-organisms. The urethanes of formula (1) may accordingly be used as stabilizers for organic materials, for example as protection agents against ultraviolet radiation and oxidation influences, and simultaneously especially as materials for combatting harmful micro-organisms on or in these organic materials. The organic materials are thereby protected against the harmful action of micro-organisms and/or optionally of ultra violet radiation, warmth, air and ox-

ygen by incorporating the urethanes of formula (1) into the materials protected, applying them to their surface or introducing a filter layer in front of these materials.

The materials for combatting harmful micro-organisms, which contain urethanes of formula (1), may be manufactured and used in the usual manner which is in itself known. A particularly valuable aspect of the new materials is the broad antibacterial spectrum of activity which in many compounds extends to both gram-positive and gram-negative bacteria. At the same time the freedom from odor and color of the urethanes of formula (1) is of particular value in respect of use technology. The present invention thus also comprises their use for pest control quite generally. This use is possible on a very broad basis, especially for protecting organic substrates against attack by destructive and pathogenic (including phytopathogenic) micro-organisms. The compounds of formula (1) are accordingly suitable for use both as preservatives and as disinfectants for textiles and technical products of all kinds, in plant protection, in agriculture, in veterinary medicine and in cosmetics.

Amongst the technical products which can be preserved with the aid of compounds of formula (1) the following may be selected as examples: textile auxiliary agents or finishing agents, glues, binders, paints, color pastes or printing pastes and similar preparations based on organic and inorganic dyestuffs or pigments, including those which contain casein or other organic compounds as admixtures. Wall and ceiling paints, for example those containing a color binder which contains albumen, are also protected against attack by pests by an addition of the new compounds. It is also possible to use them for timber protection.

Furthermore, compounds of formula (1) may be used for a preservative and disinfectant finish of fibers and textiles, wherein they may be applied to natural and synthetic fibers and there display a lasting effect against harmful (including pathogenic) organisms, for example fungi and bacteria. In this, the addition may be effected before, simultaneously with, or after treating these textiles with other substances, for example color or printing pastes, finishes and the like.

Textiles treated in this way also show protection against the occurrence of perspiration odor such as is occasioned by micro-organisms.

The compounds of formula (1) may also be used as preservatives in the cellulose and paper industry, interalia for preventing the known slime formation, caused by micro-organisms, in the equipment used for obtaining paper.

Furthermore combination of compounds of formula (1) with detergentlike or surface-active substances leads to washing and cleaning agents having excellent antibacterial or antimycotic action. The compounds of formula (1) may for example be incorporated into soaps, or combined with soap-free detergentlike or surface-active substances or with mixtures of soaps and soap-free detergentlike substances, with their antimicrobial activity remaining fully preserved in these combinations.

Cleaning agents containing compounds of formula (1) may be employed in industry and in the household, and also in the foodstuff industry, for example in dairies, breweries and abattoirs. The urethanes of formula (1) may also be used as a constituent of preparations which are used for cleaning or disinfection purposes.

The action can also be utilized in preservative and disinfectant finishes of plastics. When using plasticizers it is advantageous to add the compounds of formula (1) to the plastic with the compounds dissolved or dispersed in the plasticizer. It is appropriate to ensure that the material is as uniformly distributed in the plastic as possible. The plastics having antimicrobial properties may be used for utensils of all kinds in which effectiveness against the most diverse germs, such as for example bacteria and fungi, is desired, as for example in door-mats, bathroom curtains, toilets, foot grids in swimming baths, and wall coverings. The incorporation in wax and polishing compositions results in floor polishes and furniture polishes

having a disinfectant action.

The compounds of formula (1) may be applied to textile materials to be protected in the most diverse manner, for example by impregnation or spraying with solutions or suspensions which contain the compounds mentioned as the active substance. The active substance content may herein, depending on the end use, lie at between 1 and 30 g. of active substance per liter of treatment liquid. In most cases textile materials of both synthetic and natural origin are adequately protected against attack by fungi and bacteria by a content of 0.1 to 3 percent of active substance. The active substance may be employed together with other textile auxiliary agents such as finishing agents, crease-proof finishes and the like.

The use forms can correspond to the usual formulations of pesticides; for example, agents containing a compound of formula (1) may optionally further also contain additives such as carriers, solvents, diluents, dispersing agents, wetting agents or adhesives and the like, as well as other pesticides.

It is also possible, in principle, by means of the compounds described under formula (1), to stabilize and protect all those organic materials which are in any way damaged or destroyed by the influence of ultraviolet radiation. Such damage by the action of the same cause, namely ultraviolet radiation, can have very diverse results, for example color change, change in mechanical properties (brittleness, tendency to crack, tear strength, flexural strength, abrasion resistance, elasticity and ageing), the initiation of undesired chemical reactions (decomposition of sensitive chemical substances, for example medicines, photochemically induced rearrangements, oxidation and the like (for example of oils containing unsaturated fatty acids), the inducing of burn phenomena and irritations (for example in the case of human skin) and many others. Great importance attaches to the use of the compounds of formula (1) for protecting polycondensation products and polyaddition products against the action of ultraviolet. Furthermore a whole series of the compounds defined above also shows, alongside the said ultraviolet protective action, a stabilizing effect against the action of oxygen and heat.

The organic materials to be protected may be in the most diverse processing states and states of aggregation, whilst their common characteristic consists of a sensitivity towards ultraviolet radiation.

Where the protective agents of formula (1) which are to be used are to be employed for the treatment of organic textile materials of natural or synthetic origin, for example textile fabrics, they may for this purpose be applied to the substrate to be protected by fixing processes resembling dyeing processes in each phase of the final processing, such as finishing, crease-proofing, dyeing processes or other finishing.

The new stabilizing agents of formula (1) which are to be used are preferably added to, or incorporated in, the materials before or during their shaping. Thus they may for example, in the case of the manufacture of films, foils, strips or shaped articles, be added to the compression-moulding or injection-moulding composition or be dissolved, dispersed or otherwise

finely divided in the spinning composition before spinning. The protection agents may also be added to the starting substances, reaction mixtures or intermediates for the manufacture of fully synthetic or semisynthetic organic materials, thus 5 also including addition before or during the chemical reaction, for example in the case of a polycondensation (thus also to precondensates), in a polymerization (thus also to prepolymers) or in a polyaddition.

It is obvious from the foregoing that in addition to the protection of the substrate or the carrier substance which contains the ultraviolet absorption agent, the protection of other concomitant substances of the substrate is also simultaneously achieved, for example of dyestuffs, antioxidants, disinfectant additives, antistatic agents and other finishes, plasticizers and fillers.

Depending on the nature of the substance to be protected or stabilized, and on its sensitivity or the form of protection and stabilization in respect of application technology, the requisite 10 quantity of stabilizer may vary between wide limits, for example between about 0.01 to 10 percent by weight relative to the amount of substrate to be protected. For most practical purposes amounts of about 0.05 to 2 percent however suffice.

The process for protection of organic materials against the 15 action of ultraviolet radiation and heat which results from the foregoing thus consists of homogeneously distributing the compounds defined above in the organic materials to be protected, applying them to the surface of these materials or coating the materials to be protected by a filter layer which contains the compounds described.

If the substance of formula (1) which is to be used is to be applied to the surface of the substrate to be protected, such as for example a fiber material (fabric), then this can advantageously be effected by introducing the substrate to be protected into a liquor which contains the ultraviolet absorption agent in a dissolved or dispersed form. Suitable solvents may for example be methanol, ethanol, acetone, ethyl acetate, methyl ethyl ketone, cyclohexanol or especially water. The substrate to be treated is, similarly to the case of dyeing 20 processes, left in the liquor at 10° to 120° C. for a certain time—10 minutes to 24 hours suffice in most cases—it being possible optionally to agitate the liquor at the same time. Thereafter the material is rinsed, optionally washed and dried.

The parts and percentages mentioned in the examples 25 which follow are units by weight.

EXAMPLE I

10.7 parts of 2,4-dihydroxy-benzophenone are dissolved in 50 150 parts of benzene at 70° C. After adding 0.2 parts of 1,4-diazabicyclo-[2.2.2]-octane, 11.1 parts of 4-chloro-5-trifluoromethyl-phenyl-isocyanate are added dropwise over the course of 20 minutes at 60° C., whilst stirring. The mixture is stirred for a further 3 hours at the same temperature, cooled to 15° C., and the colorless reaction product is filtered off.

After once recrystallizing from toluene-hexane, 18 parts of the urethane of formula (8) are obtained. Melting point 162° to 163° C.

The urethanes of formulas (6), (9) to (11) and (16) to (38), 60 whose melting points are summarized in table I, are manufactured analogously.

Legend to Table I:

Column I = Formula number
Column II = A— in formula
Column III = —R
Column IV = Melting point in ° C.

EXAMPLE 2

Determination of the minimal inhibitory concentration (MIC) against bacteria and fungi in the dilution test.

The determination of the MIC (minimal inhibitory concentration) is effected according to a test derived from Standard Specifications, which permits an approximation to absolute minimal inhibitory values of an active substance.

An 0.4 percent strength, and an 0.12 percent strength solution in dimethyl sulfoxide are produced from the active substances. 0.25 ml. of the respective solutions are added to 9.75 ml. of sterile Brain Heart Infusion Broth (bacteria) or beer wort solution (fungi). The two series obtained by progressive dilution by ten-fold in each case are combined and thereby converted to the following continuous dilution series:

100, 30, 10, 3 and 1 p.p.m. of active substance.

The solutions are inoculated with the bacterium *Staphylococcus aureus* and the fungus *Rhizopus nigricans*. Thereafter incubation is effected for 48 hours at 37° C. in the case of the bacterium (bacteriostasis) and for 72 hours at 30° C. in the case of fungus (fungistasis).

After the times mentioned, the minimal inhibitory values (p.p.m.) of table II are found.

TABLE II

Compound of Formula No.	Minimal inhibitory concentration (MIC)	
	<i>Staphylo-</i> <i>coccus</i> <i>aureus</i>	<i>Rhizopus</i> <i>nigricans</i>
(8).....	0.1	<100
(10).....	0.3	>100
(11).....	0.1	<100

EXAMPLE 3

A film of approximately 60 μ thickness is manufactured from a 10 percent strength acetone solution of acetylcellulose which contains 2 percent of the compound of formula (9), calculated relative to acetylcellulose. After drying the following values are obtained for the percentage light transmission.

TABLE III

Wavelengths in μ	Light transmission in percent	
	Not exposed to light	Exposed to light (100 hours Fadeometer)
280 to 340.....	0	0
360.....	4	4
360.....	15	15
370.....	45	45

Similar results are for example obtained with the compounds of formulas (8), (10), (11) or other compounds according to the invention mentioned in the description, provided these compounds are dissolved in the acetylcellulose.

EXAMPLE 4

x p.p.m. of the compounds of formula (1), in a suitable formulation, are added to the Brain Heart Infusion Agar (BHIA) whilst the latter is still liquid. This liquid mixture is cast onto a base agar nutrient layer (BHIA) without active substance which beforehand had been inclined for solidification, and was allowed to solidify.

For inoculation, the germs to be tested are applied at right angles to the gradient, in the form of a line, by means of a

Pasteur pipette.

After 24 hour incubation at 37° C. the length of the germs which have grown on the inoculation line is measured and expressed in p.p.m. of active substance. The following results were obtained by this test method:

TABLE IV

Compound of formula.....	Minimal inhibitory concentration (p.p.m.)			
	(8)	(10)	(11)	(6)
Test organism:				
Streptococcus mitis.....	0.4	0.2	2	5
Trichophyton interdigitale.....	2	30	4	2
Trichophyton mentagrophytes.....	25	25	3	2

EXAMPLE 5

Samples of 100 g. cotton cretonne are impregnated at 20° C., on a padding machine, with an 0.1 percent strength isopropanol or dioxane solution of the compounds of formula (1) and subsequently squeezed out with 100 percent liquor uptake.

The fabrics dried at 30° to 40° C. contain 0.1 percent of active substance relative to their own weight.

In order to test the action against bacteria, 10 mm. diameter discs of the impregnated fabrics, unsoaked and after soaking, are laid for 24 hours at 29° C. onto Brain Heart Infusion Agar plates which are inoculated beforehand with *Staphylococcus aureus*. The plates are thereafter incubated for 24 hours at 37° C.

The inhibitory zone (Hz. in mm.) occurring around the discs is assessed on the one hand, and the microscopically determinable growth (W in percent) under the fabric or on the fabric is assessed on the other hand.

TABLE V

Compound No.:	Unsoaked		Soaked	
	Hz. in mm.	W in percent	Hz. in mm.	W in percent
8.....	1	0	1	0
10.....	0	0	0	0
11.....	1	0	1	0

We claim:

1. A urethane of the formula

wherein X represents a hydrogen atom, a chlorine atom, a hydroxyl group and an alkyl group having one to four carbon atoms, Y represents a hydrogen atom, a chlorine atom, a hydroxyl group, an alkyl group having one to four carbon atoms, a methoxy group and an R—NH—CO— radical, Z represents a hydrogen atom, a chlorine atom, a phenyl group and an alkyl group having one to four carbon atoms and R denotes a member selected from the group consisting of an alkyl group having one to 12 carbon atoms alkenyl having two to four carbon atoms and a radical of the formula

wherein U, V and W each represents a member selected from the group consisting of a hydrogen atom, a halogen atom, a trifluoromethyl group, an alkyl group having one to four carbon atoms and an alkoxy group having one to four carbon atoms.

2. A urethane according to claim 1 wherein W is hydrogen and U and V each represents a member selected from the

group consisting of a hydrogen atom, a halogen atom, a trifluoromethyl group, a methyl group and a methoxy group.

3. A urethane according to claim 1 of the formula

5 10 wherein X represents a hydrogen atom or a hydroxyl group, Y represents a member selected from the group consisting of a hydrogen atom, a chlorine atom, a methoxy group, a phenyl group, an alkyl group having one to four carbon atoms and an R—NH—CO—O— radical and R denotes a member selected from the group consisting of an alkyl group having one to 12 carbon atoms, an alkenyl group having two to four carbon atoms and a radical of the formula

15 20 wherein U, V and W each represents a member selected from the group consisting of a hydrogen atom, a halogen atom, a trifluoromethyl group, an alkyl group having one to four carbon atoms and an alkoxy group having one to four carbon atoms.

4. A urethane according to claim 1 of the formula

25 30 wherein U and V each represents a member selected from the group consisting of a hydrogen atom, a halogen atom, a trifluoromethyl group, a methyl group and a methoxy group.

5. The urethane according to claim 1 of formula

6. The urethane according to claim 1 of formula

7. The urethane according to claim 1 of formula

8. The urethane according to claim 1 of formula

UNITED STATES PATENT OFFICE
CERTIFICATE OF CORRECTIONPatent No. 3,622,618 Dated November 23, 1971Inventor(s) MAX DUENNENBERGER ET AL

It is certified that error appears in the above-identified patent and that said Letters Patent are hereby corrected as shown below:

Column 11, line 57, change "R-NH-CO-)" to read

--- R-NH-CO-O- ---;

Column 12, claim 6 in the formula, change "CF3" to
read --- CF₃ ---.

Signed and sealed this 13th day of June 1972.
